UNITED STATES PATENT OFFICE

JOHN M. LEA, OF DETROIT, MICHIGAN

PUMPING MECHANISM

Application filed January 12, 1929. Serial No. 332,061.

This invention relates to pumping mechanisms and particularly to such mechanism as is applicable for supplying fuel to the carburetor of internal combustion engines, or for like purposes, the principal object being the provision of certain novel features of construction which will aid in providing a device of superior operation, of simple construction, and in which it will be substantially impossible to wrongly assemble the same, or if wrongly assembled, will not affect the operation of the device.

Another object is to provide, in combination with a pumping mechanism having a pumping element power actuated in one direction and spring actuated in the opposite direction, means for readily and quickly varying the spring pressure whereby to vary the discharge pressure of the pump.

Another object is to provide a connecting organization comprising a spring hinge member of novel construction whereby the life of the spring is materially increased over conventional constructions.

Another object is to provide a liquid filtering device in which misplacement of the filtering element will not act to cut off the flow of the liquid being filtered.

Another object is to provide a novel form of valve structure.

A further object is to provide a pumping mechanism of the electrically operated type wherein certain novel features of construction, as will hereinafter be apparent, are included.

The above being among the objects of the present invention, the same consists in certain features of construction and combinations of parts to be hereinafter described with reference to the accompanying drawings, and then claimed, having the above and other objects in view.

In the accompanying drawings which show a suitable embodiment of the present invention, and in which like numerals refer to like parts throughout the several different views:

Fig. 1 is a partially broken side elevation of my improved pumping device.

Fig. 2 is a vertical sectional view taken on the line 2—2 of Fig. 1.

Fig. 3 is a horizontal sectional view taken through the body of the device as on the line 3—3 of Fig. 2.

Fig. 4 is an enlarged vertical sectional view taken through one of the check valves employed in the device.

Fig. 5 is a sectional view taken on the line 5—5 of Fig. 4.

Fig. 6 is a sectional view taken on the line 6—6 of Fig. 4.

Fig. 7 is a side view of the valve shown in Figs. 4 to 6 inclusive.

Fig. 8 is a rear view of the spring hinge member employed in connecting the armature to the yoke of the motor portion of the device.

Fig. 9 is an enlarged sectional view taken on the line 9—9 of Fig. 8.

Fig. 10 is a view similar to Fig. 9 but showing a modified form of the construction.

Fig. 11 is a partially broken fragmentary view showing the connection between the bellows, connecting stud and the armature when modified for a two wire electrical system.

Fig. 12 is a fragmentary perspective view of the upper end of the post member secured to the upper face of the body and particularly showing the lugs provided for preventing the filtering element from shutting off the inlet passages should the filtering element be misplaced.

Fig. 13 is a fragmentary sectional view of the lower end of the magnet core illustrating how the spacer member may be reversed to cut down the discharge pressure of the pumping device, and the manner in which the spacer member cooperates with the spring stop when in reversed position.

Fig. 14 is a top view of the motor taken as on the line 14—14 of Fig. 1.

Fig. 15 is a fragmentary sectional view taken on the line 15—15 of Fig. 2 and showing the path of the fuel entering the device.

Fig. 16 is a vertical sectional view taken on the line 16—16 of Fig. 15.

Fig. 17 is a fragmentary vertical sectional view taken through the center of the armature to show the manner in which the arma-

ture is formed immediately adjacent the stud which connects the same to the bellows.

Fig. 18 is a plan view of the lower face of the portion of the armature shown in Fig. 17.

The present invention relates to a pump mechanism constructed in substantial accordance with the construction shown and described in my Patent Number 1,570,381 issued January 19th, 1926 on pumping mechanism, and deals particularly with certain improvements as applied thereto whereby an improved device is provided.

The device comprises in general a pumping element preferably, but not necessarily, of the metallic bellows type in which movement of the bellows on its suction stroke is effected by means of a magnet, and the movement of which on the discharge stroke is effected by means of a spring controlled to produce a substantially constant and predetermined discharge pressure of the liquid being pumped, together with suitable means for filtering the fuel passing through the pump and for regulating its course of travel through the same.

Referring to the drawings and particularly to Figs. 1, 2 and 3, the device is provided with a main body portion 30 through which extend two spaced vertical openings 31 and 32 respectively. The opening 31 is provided with a shoulder 33 at approximately midway its depth, and the opening 32 is provided with a similar shoulder 34 at its lower end. A fuel inlet passage 35 connects with the opening 31 and a fuel outlet passage 36 connects with the opening 32. Secured to the upper face of the body 30 by screws (not shown) threaded into the openings 37 in the body member 30 (see Fig. 3) is a member 38 having a horizontally extending flange portion 38 separated from the body portion 30 by a suitable gasket 39, and having an upwardly extending central portion 40. Projecting downwardly from the under face of the flange 38 are two bosses 44 and 45 respectively, spaced so as to be receivable in the openings 31 and 32 respectively. The lower face of the boss 44 is adapted to clamp the outwardly extending flange 46 of the check valve body 461 against the seat 33 to hold the same in place in the opening 31, a suitable gasket being provided between the flange 46 and shoulder 33 to prevent possibility of leakage. The boss 45 is hollowed out to permit the outlet check valve to be positioned therein, and its lower edge which is notched as at 47 to permit the flow of fuel through it, bears against the flange 48 of the check valve body 49 and clamps it against the shoulder 34.

Referring to the construction at the inlet passages it will be noted that the boss 44 is substantially smaller in diameter than the opening 31 so as to provide an annular passage 50, best shown in Fig. 15, between the

boss and the walls of the opening 31, and this annular passage is sealed from that portion of the opening 31 below the shoulder 33 by the flange 46 of the inlet check valve. The annular chamber 50 is connected by a pair of openings 51, which terminate short of the lower face of the boss 31 and which extends upwardly through the member 40 in the form of tubes 52, as indicated in Fig. 12, to the upper end of the member 40 where the fuel discharges into a sub-atmospheric chamber 57 formed by the inverted bell 53, the open edges of which are pressed against the gasket 54 on the flange 36 by means of the bolt 55 projecting through the closed end of the bell 53 and threaded into the upper end of the member 40. A discharge opening 56 for the sub-atmospheric chamber is formed centrally of the boss 44 and extending from the upper face of the flange 38 to the lower face of the boss 44 so as to discharge to the inlet check valve. A filtering member preferably comprising a tube 60 of fine wire mesh and an imperforate end 61 surrounds the member 40 and encloses the opening 46, its upper-end 61 being perforated so as to slip over the upper ends of the tube portions 52 and the upwardly extending boss portion 62 of the member 40 into which the screw 55 is threaded. The filtering member is constantly urged against the flange 36 by means of a coil spring 63 held under compression between the washer 64 interposed between the bell 53 and the head of the screw 55, and the upper wall 61 of the filter.

The flow of fuel in the construction thus far described is as follows: The fuel enters the passage 35 and into the annular chamber 50 formed about the boss 44 and, entering the openings 51, flows upwardly and is discharged into the sub-atmospheric chamber 57 above the upper wall 61 of the filtering element, and then flows through the filtering element 60 and thence into the opening 56. In order to prevent possibility of the upper wall 61 of the filtering element from closing off the upper ends of the tubular passage 52 should the filtering element be improperly assembled so that the tubular portions 52 do not project through the upper wall of the filtering element 61, each tubular portion 52 is provided with an upwardly projecting lug 65 at its upper end, best shown in Fig. 12, and which serves to hold the end 61 out of complete contact with the upper end of the portions 52 when such misplacement occurs, thus preventing the flow of fuel from being interrupted when the filtering element is misplaced, even though the effectiveness of the filter in such case is destroyed.

The fuel flowing downwardly through the passage 56 from the sub-atmospheric chamber passes through a check valve structure positioned in the lower portion of the

- opening 31 and which will be described in detail later, and thence into the pumping chamber which may take any suitable form, but which is shown in the present case as comprising the interior of a metal bellows 66 whose open end is secured against leakage to the under face of the body 30 by means of a clamping frame 67 suitably secured to such face by screws (not shown).
- 10 The lower end of the bellows 66 is, of course, closed and connected to a suitable source of power as will be later described. The body member 30 is preferably provided with a central downwardly extending boss portion 79 which acts to fill the interior of the bellows 66 to the greatest possible extent without interfering with its proper action. The boss 79 is provided in order to cut down the available volume within the bellows in which air may be expanded and compressed when the pump is being primed, thereby facilitating the priming of the pump. The action of the bellows which is the same as in my previous patent referred to above, is as follows:
- When the bellows is expanded a suction is created within the same, which in turn creates a suction in the passage between itself and the inlet passage 35 and causes a consequent flow of fuel into the bellows, and when the bellows is contracted the fuel which has been drawn into it is placed under pressure and forced through the various passages and out of the outlet passage 36.
- 35 The check valves previously referred to insure the flow of the fuel in the proper direction.
- The construction of the check valves
- cage is preferably apertured, and the metal at the margins of the aperture downwardly turned as at 76, and a light coil spring 77 is held under compression between the valve disc 70 and the body 71 of the cage to maintain the disc 70 normally against the seat 69, and is held in central position by embracing the downturned margin 76. Between the arms 72 the body portion 71 of the cage is preferably provided with one or more 75 downwardly extending lugs 78 adapted to cooperate with the valve disc 70 to limit its opening movement.
- It will be apparent that this form of valve construction is exceedingly simple and readily assembled and disassembled, the cage being assembled to the body merely by pressing it onto the body. The valve disc member 70 is preferably formed of some light substance resistive to the effects of the fuel, such as the commercial product known to the trade as "bakelite", and which because of its smooth surface does not require finishing after punching. I have further found that in such check valves, due to the swirling of the fuel passing through the same, that unless the valve disc is prevented from rotating, an excessive wear of the parts occurs, and the method herein employed for preventing rotation of the valve disc is both simple and effective.
- It will be noted from an inspection of Fig. 2 that in employing this form of check valve construction and in placing them as described in the device, it is impossible to assemble the flange member 38 to the body 30 with the valves in wrong position and it is further impossible to place the flange member 38 on the

identified. The magnet comprises a core 83 provided with an end piece 84 of insulated material at its upper end and another member 85 of insulated material at its lower end, the windings 86 being interposed therebetween. The upper member 84 extends out past the outer limits of the windings 86 and forms a means of securing the motor in place relative to the body of the device, this being accomplished by means of screws such as 87 which pass up through the member 84 and are threaded into the downwardly extending legs 88 depending from the member 67, which as previously described, is secured to the main body portion 30 by means of screws (not shown). Instead of employing the housing for the motor as a yoke as was done in the construction shown in my previous patent, in the present construction I provide a separate yoke 89 which is secured to the lower end of the core 83 and extends up over the top of the magnet core where it is connected to the top of the core. From the upper end of the yoke 89 the armature 90 is supported by a means which will be described later, and the flexible arm 91 carrying the contact 92 at one end thereof is secured to the armature 90 at the opposite end by rivets such as 93, or other suitable means. Limitations of construction make it desirable to construct the armature 90 of thinner metal than is required for the proper magnetic path through it. Consequently the armature 90 is reinforced by a relatively thick steel member 94 on its upper surface. A yoke member 95 secured to the end member 84 and extending over the contact end of the arm 91 is provided with a contact 96 suitably connected to the magnet winding and positioned to engage the contact 92. The bellows 66 is provided with a central downwardly extending apertured pin 97 secured to the lower wall thereof and a stud member 98 extending through the central aperture 99 in the armature 90 is threaded into the same. The stud member 98 is provided with a shoulder 100 immediately below the armature 90 for engagement with the lower face of the armature 90 and a washer 101 is preferably provided between the shoulder 100 and the armature 90. The stud 98 extends downwardly from the shoulder 100 and terminates in a head 102 freely positioned within the central opening 103 in the core 83. The threaded connection between the pin 97 and stud 98 permits adjustment of the relative position of the bellows 66 with respect to the armature 90, the stud 98 being locked in adjusted position by means of a lock nut such as 104.

60 The lower face of the yoke 89 is provided with a spring stop member 108 swingably secured thereto by a rivet such as 107 or other suitable means, and has an end adapted to normally be positioned across the lower end 65 of the core 83. This end is formed with a

depression 109 therein and an opening 110 concentric with the depression 109. A spacer member having a cylindrical tubular body portion 111 and a reduced extending portion 112 separated by a shoulder 113 is positioned in the enlarged lower end 114 of the bore 103 of the core 83 and seats against the stop member 108, a coil spring such as 115 being positioned in the bore 103 and being held under compression between the spacer member 111 and the head 102 of the stud 98. The action of the spring 115 acting through the stud 98 and pin 97 is, of course, to compress the bellows 66 so as to cause the liquid therein to be discharged through the outlet opening 36, the pressure of the liquid in the discharge opening 36 being a direct function of the force exerted by the spring 115 against the bottom of the bellows. The force with which the spring acts upon the bellows may, of course be varied by the employment of various springs of desired weight to obtain the pressure desired, or may be varied by means of a threaded plug such as is shown in my previous patent, but where the device is to be employed for furnishing fuel to the carburetor of an internal combustion engine, the discharge pressure of the fuel at the opening 36 is preferably between one and two pounds per square inch, and in the present case the employment of the spacer member 111 permits a quick and ready means for changing the pressure of the spring 115 to any two predetermined values. This is accomplished in the following manner:

Referring to Fig. 2 it will be noted that the lower end of the enlarged portion 111 of the spacer is seated in the depression 109 of the stop member 108 with the reduced extension 112 projecting upwardly, the spring 115 surrounding the portion 112 and being seated against the shoulder 113. The lower end of the spring is accordingly spaced from the stop member 108 an amount corresponding to the height of the enlarged portion 111 of the spacer, and this results in a predetermined amount of compression of the spring 115. However, if the spacer member is reversed from the position shown in Fig. 2 to that position shown in Fig. 13, the projecting portion 112 then projects through the opening 110 in the stop member 108 with the shoulder 113 resting directly against the upper face of the stop member, and the spring 115 in this case is received within the enlarged portion 111 of the spacer member and against the opposite face of the shoulder 113. In other words, in this position the lower end of the spring 115 is spaced from the upper face of the stop member 108 by only the thickness of the metal of the spacer member at the shoulder 113. It will be readily apparent that the spring 115 in this case is under considerably less compression stress than when the spacer member is positioned as indicated in Fig. 2.

It will be noted that when the spacer member is in the position shown in Fig. 2 the lower end of the enlarged portion 111 is received in the depression 109 and thereby acts to prevent inadvertent swinging of the stop member 108 away from under the core, and that when the spacer member is positioned as indicated in Fig. 13 the projecting portion 112 extends through the opening 110 and similarly acts to prevent inadvertent swinging movement of the stop member 108. It will be apparent that in either of its reversed positions, the spacer member cooperates with the bore 114 and spring 115 to insure a concentric relation of these parts and maintains the spring 115 out of frictional contact with the bore 114.

If it is desired to remove the spacer member in order to reverse it, or to remove the spring 115, all that is necessary is to insert a pin through the opening 110 in the first case, and raise the spacer member sufficiently to allow the arm 108 to be swung, and in the second case merely to lift the projecting end 112 up out of the opening 110. The enlarged portion 114 of the yoke 103 is provided so that a shoulder 116 past which the spacer member cannot go will be provided between the top and bottom of the core 83, this being done in order to prevent possibility of the spacer member being inserted in the bore previous to insertion of the spring 115, which would cause trouble in the operation of the device.

The movement of the bellows 66 on the suction stroke is, of course, accomplished against the pressure of the spring 115 by the passage of an electrical current controlled by the contacts 92 and 96 through the magnet winding, which acts to magnetize the core 83 and to draw the armature 90 downwardly, moving the stud 98 and pin 97 with it through contact with the shoulder 100 and the washer 101. An appreciable travel of the bellows 66 is obtained on the suction stroke by the employment of the steel collar 119 secured to the spring arm 91 about the stud 98 acting to flex the arm 91 upwardly upon passage of current through the contacts 92 and 96, as fully described in my previous patent above identified.

In accordance with the present invention, I employ a novel pivotal support for the armature 90 on the yoke 89, this being of that type employing a flat spring member to swingably connect two members together. In employing such a spring connection the usual practice is to clamp one side of the spring rigidly between two flat surfaces to one member and the opposite side of the spring rigidly between two flat surfaces on the other member, such members being spaced from each other adjacent the center of the spring member a greater or lesser amount so that the portion of the spring member ex-

posed is employed as the bending element permitting movement of one of the members relative to the other. By this method of construction in conventional constructions all the stresses in the spring are localized in that portion thereof exposed between the two members connected thereby. Consequently this portion is liable to be subjected to excessive stresses and is also liable to offer a greater amount of resistance to bending than is desirable in many cases. In accordance with the present construction I so form this type of joint that the rigidity and resistance to deflection, except in the direction desired, is as great as in the conventional constructions, yet the spring is permitted to flex over a much greater length in the direction desired whereby a longer life of the spring is assured and less resistance to movement of the connecting parts is offered for a spring of given section.

The means by which I accomplish this result is best described in connection with the construction shown in the drawings. Referring to Figs. 1, 8, 9 and 14, it will be noted that to the upper face of the yoke 89 a member 120 is secured by means of screws such as 121 (see Fig. 14) extending through openings 122 therein, the openings 122 being substantially larger than the screws 121 to permit the member 120 and thus the armature 90, spring member 91, contact 92 and collar 119 to be shifted to proper position in assembly. The member 120 is provided with a downwardly bent portion 124 which extends down the side of the yoke 89. A flat spring 125 is clamped against the downwardly extending portion 124 by means of a block or plate 126. The right hand end of the armature 90, as viewed in Figs. 8, 9 and 14, is turned upwardly as at 127 and the upper end of the spring 125 is clamped against the portion 127 by means of a block or plate 128. In conventional constructions the spring 125 would contact with both the portions 124 and 127 over the entire area of the same, as does that portion of the spring 125 in contact with the portion 127 of the armature 90 so that there is no possibility of that portion of the spring 125 enclosed between the clamping plate 128 and the portion 127 flexing. In the present case however, the member 120 is so formed that a projecting bead 129 is provided at the point of bending of the part 125 and the portion 124 is relieved as at 130 between the bead 129 and the lower end of the member 124. The clamping plate 126 acts to rigidly clamp the lower end of the spring 125 between it and the lower end of the portion 124 and extends up to the bead 129 where it clamps the spring 125 against the bead 129. With this construction, when the free end of the armature 90 is raised, as is done by the spring 115 in this case, the spring 125 instead of flexing only between 130

the adjacent edges of the clamping plates 126 and 128, flexes for the entire distance between the lower edge of the clamping plate 128 and the lower limit of the recessed portion 130.

- 5 By this construction the stresses set up in the spring 125 are materially lessened over that of conventional constructions, and yet by clamping the spring at the bead 129 the construction is equally resistive to undesirable 10 movement of the spring as in conventional constructions.

The spring 125 is preferably relatively wide in proportion to its length, and the plate 126 is preferably initially formed to insure 15 positive clamping of the spring 125 at its outer edges between the plate 126 and bead 129 to give it rigidity against magnetic unbalance.

It will be apparent that the clamping plate 20 126 may be relieved in a manner similar to the portion 124 where the spring 125 flexes to both sides of a single plane, but inasmuch as in the construction shown the spring 125 flexes only to one side of such a plane, such 25 relief is not necessary.

It is of course not necessary that the spring 125 be positioned perpendicularly with respect to the path of movement of the armature 90, as indicated in Figs. 8 and 9, this 30 being done in the construction shown in order to make the motor more compact and to facilitate concentric adjustment of the armature, but it will be apparent that the construction may be modified to best suit the conditions met or the desires of the particular 35 designer. For instance, it may be modified as indicated in Fig. 10 in which a member 134 similar to the member 120 is secured by screws such as 135 to the side face of the yoke 89, the member 134 being provided with a bent portion 136 having a bead 137 and recessed portion 138 in exactly the same manner as the portion 124, bead 129 and recess 130 of the member 120. The spring 139 in 40 this case lies in a substantially horizontal plane and is clamped to the member 134 by a plate 140, its other end being clamped directly against the armature 90 by a plate member such as 141. The member 134 is 45 provided with openings 142 therein in which the screws 135 are freely received, thus permitting the armature and cooperating parts to be shifted relative to the yoke within the limits of clearance between the walls of the 50 openings 142 and the screws 135 to properly adjust the contacts 92 and position the collar 119 in the openings 103 in the core 83, or to 55 vary the air gap between the armature and core.

60 In securing a flat spring between a pair of clamping members as above described, the usual method is to secure the two clamping members together with rivets such as 143. This method is not altogether satisfactory 65 for the reason that the spring has a tendency

to work between the clamping members and, bearing against the rivets, cause them to wear through at the point where they contact with the spring and allow subsequent shifting of the spring with attendant loss of 70 adjustment. This wearing action is of course relatively slow, but in constructions particularly designed for long life it offers a serious problem. In the present invention, I have provided a construction which eliminates this wear of the rivets, and referring 75 to Figs. 8 and 9, is as follows:

The spring 125 at one or more points between the rivets 143 which secure the plate 128 to the portion 127 of the armature 90 80 is provided with an opening such as 144. After the plate 128 has been riveted to the portion 127 of the armature 90 a punch is employed to strike the surface of the plate 128 directly over the openings 144. This causes the surface of the plate 128 at these points to be depressed as at 145 and causes the metal at such points to flow into and completely fill the corresponding openings 144 as at 146. This has the effect of locking the 85 spring 125 to the plate 128 so as to effectively prevent creeping of the spring relative to the plate, and thus relieves the rivets 143 from any wear due to this cause. The spring 125 is likewise provided with one or more openings 147 between the rivets 143 passing through the plate 126, and the plate 126 is 90 operated upon by a punch to form a depression 148 and a portion 149 of the metal is forced into the opening 147 in the same manner as described above. It is, of course, obvious that the portions 127 and 124 may be extruded through the openings in the spring 125, instead of the members 128 and 126 respectively, and this may be preferable in 95 some cases because of the more direct connection between the parts affected.

Inasmuch as the armature 90 has a pivotal action upon a line in the neighborhood of the spring 125, between the plates 126 and 128, 100 and due to the fact that the stud 98 is limited to straight line motion, a rocking action occurs between the washer 101 and the under surface of the armature 90. Unless otherwise provided for, due to the different movements 105 of the stud 98 and armature 90, the contact between the armature 90 and the washer 109 might be limited to that edge of the washer 101 nearest the line of pivot of the armature 90 and would be liable to cause undesirable 110 localized wear. In order to overcome possibility of trouble from this standpoint, I counterbore the under surface of the armature 90 immediately around the opening 99 so as to provide a partially conical surface 150, best 115 shown in Figs. 17 and 18, whereby to provide a rolling contact between the armature 90 and the washer 101, thus insuring satisfactory 120 cooperation between these two parts. The washer is provided, among other things, for 125

equalizing the wear between the armature and the shoulder 100.

In the construction shown in Figs. 1 and 2, the device is shown as wired up for what is conventionally known as one-wire, or ground return circuit, such as is adaptable for use in connection with motor vehicles in which the frame and body of the vehicle and other mechanical parts are employed as the return side of the electrical circuits. In such a case a single wire such as 151 from the positive side of the source of electric current extends through the flared opening 152 in the housing or cover 153 secured to the member 67 by screws such as 154, and which serves as a casting or cover for the motor. The wire 151 is connected with one end of the magnet winding 86, the other end of which is suitably connected with the contact 96. When the contacts 92 and 96 are in contact with each other the current passes into the contact 92 through the spring member 91 and through the stud 98, pin 97 and bellows 66 and thence into the body member 30 which may be grounded to the frame or other part of the motor vehicle through its supporting bracket 155 which may be secured thereto by screws such as 156, or through the gasoline supply line, not shown, thus completing the electrical circuit. When it is desired to use the two-wire system it is then necessary to insulate the stud 98 from the bellows 66 in order to prevent the current from travelling through the same and the yoke 89 is then connected by a separate wire (not shown) leading to the other side of the source of electric current. The insulation of the bellows 66 from the stud 98 may be accomplished as indicated in Fig. 11 in which the bellows 66 instead of being provided with the threaded pin 97 as in Fig. 2, is provided with a short stud such as 157 upon which is threaded an interiorly threaded sleeve 158 of suitable insulating material, into which in turn the stud 98 is threaded. This provides a simple and effective means for insulating the motor from the remainder of the mechanism.

Formal changes may be made in the specific embodiment of the invention described without departing from the spirit or substance of the broad invention, the scope of which is commensurate with the appended claims.

What I claim is:

1. In combination, a pair of superposed members separated by a flat spring, said members being provided with cooperating flat faces between which said spring member is rigidly clamped against movement and further provided with cooperating portions spaced from said faces for clamping said spring therebetween along a substantially single line of contact, at least one of said members being relieved between its corresponding face and portion to permit flexing of said spring therebetween.

2. In combination, a member having a rela-

tively flat face and also a portion spaced therefrom in substantially the plane of said face, a flat spring overlying said face and portion, means clamping said spring to said face preventing flexing of said spring on said face, and means clamping said spring to said portion along a single line of contact, said spring being free to flex in at least one direction between said face and said line of contact.

3. In combination, a member having a substantially flat face and also a ridge parallel and spaced therefrom in substantially the plane of said face, a flat spring overlying said member, and a clamping member secured to the first mentioned member extending opposite both said face and said ridge but clamping said spring between itself and said first mentioned member at said face and along said ridge only.

4. In combination, a rigid member, another object and a flexible flat spring adapted to connect said member to said object, said spring being rigidly secured against movement at a point relatively remote from an edge of said member and projecting over said edge, and means, including a part extending into proximity with said edge for clamping said spring to said member adjacent said edge by line contact only, said spring being free to flex in at least one direction between said point and said edge.

5. In a connecting organization for securing a flat spring hinge member provided with a plurality of openings and disposed between a pair of clamping members each having at least one opening opposite one of the mentioned openings: a rivet extending through said clamping members and through one of said plurality of openings, said rivet being so headed as to retain said rivet to clamp said spring between said clamping members and there being a displaced portion of the metal of at least one of said clamping members extending into another of said openings.

6. In a connecting organization for securing a flat spring hinge member provided with a plurality of openings and disposed between a pair of clamping members each having at least one opening opposite one of the mentioned openings; at least one rivet extending through said clamping members and through a corresponding member of mentioned openings in said spring and so headed as to clamp said spring between said clamping members, there being a displaced portion of the metal of at least one of said clamping members so extending into another of said openings so as to substantially fill the same.

7. In a connecting organization for securing a pair of members together for relatively pivotal movement by means of a flat spring: means for rigidly clamping a material area of said spring to one of said mem-

- bers, and means for rigidly supporting it relative to said member at a point spaced from said area towards the other of said members and substantially on a single line of contact, 5 said means being so shaped as to render said spring free to flex in at least one direction between said line and said area; and means for securing the opposite end of said spring to said other of said members.
- 10 8. In combination, a pair of relatively rigid members, a flat spring extending between and resiliently connecting said members, means rigidly clamping a material area of said spring against one of said members, 15 means fixed relative to said last-mentioned member clamping said spring thereto substantially on a single line of contact spaced from said area in the direction of the other of said members, and means securing said 20 other of said members to said spring.
9. In combination with a pair of relatively movable members secured together by means of a flat spring, a support on one of said members for said spring comprising a relatively flat face of material area and a bead spaced therefrom, and means, extending into proximity with both said face and said bead, for clamping said spring against said face and said bead.
- 30 10. In combination with a pair of relatively movable members secured together by means of a flat spring, a support on one of said members for said spring comprising a relatively flat face of material area and a 35 bead spaced therefrom, and a single member, extending into proximity with both said face and said bead, for clamping said spring against said face and said bead.
11. In a connecting organization comprising a flat spring between a pair of metal members, said spring being provided with an opening in that area of said spring adapted to be concealed between said members, means for clamping said members together with said 45 spring between them, and a part of the metal of one of said members extending into said opening in said spring.
12. In a connecting organization including a flat hinge spring having an opening there- 50 in, and a member, that part of said spring surrounding said opening being placed against a face of said member, a clamping member overlying said spring and being secured to the first mentioned member and 55 concealing said opening in said spring, and part of the material from one of said members being extended into said opening.
